CLOSET TRAP FOR RAILWAY CARS

Filed April 9, 1923

INVENTOR:
Forrest L. Scott,
BY A. J. Martell
ATTORNEY.

UNITED STATES PATENT OFFICE.

FORREST L. SCOTT, OF SAN BERNARDINO, CALIFORNIA, ASSIGNOR OF ONE-HALF TO
S. B. ROSE, OF SAN BERNARDINO, CALIFORNIA, AND ONE-TENTH TO ARTHUR
LONDO, OF LAS VEGAS, NEVADA.

CLOSET TRAP FOR RAILWAY CARS.

Application filed April 9, 1923. Serial No. 630,795.

To all whom it may concern:

I, FORREST L. SCOTT, a citizen of the United States, residing at San Bernardino, in the county of San Bernardino and State 5 of California, have invented new and useful Improvements in Closet Traps for Railway Cars, of which the following is a specification.

My invention relates to closet traps for 10 railway cars by means of which the discharge passage therefrom is kept closed when the car is standing still and automatically opened for the discharge of its 15 contents when the car is running above a predetermined rate of speed. The present invention is an improvement over my railway closet trap disclosed in my application filed in the United States Patent Office 20 August 23, 1922, Serial No. 583,696.

The main object of this invention is to 25 provide a railway closet trap comprising means whereby the trap will be automatically opened quickly and locked in open position when the speed of the car reaches a pre-determined degree, and automatically closed quickly and locked in closed 30 position when the speed of the car falls below said predetermined degree.

Other objects and advantages will appear 35 hereinafter, and while I show herewith and will describe a preferred form of construction, I desire to be understood that I do not limit myself to such preferred form, but that various changes and adaptations may 40 be made therein without departing from the spirit of my invention as hereinafter claimed.

My objects are attained by the apparatus 45 illustrated in the accompanying drawing, in which:

Fig. 1 is a sectional elevation taken through the longitudinal center of a railway car on which my invention is installed; and Fig. 2 is a plan view of the operating 50 lever of my trap.

Similar numerals refer to similar parts throughout both views.

In the drawing 1 indicates the floor of 55 a railway car and 2 a portion of the end of one of its trucks. A toilet bowl 3 of any suitable type is mounted upon the floor 1 within the car. The bowl 3 discharges into a chute 4 which leads into a bottom dumping hopper 5 secured at its upper end to

the under side of the floor 1. The lower 55 end of the hopper 5 is closed by an inclined door 6 hinged at 7 to one side of said hopper and inclining downwardly from said hinge. The door 6 has a rubber valve-shaped head 6^a on its upper side which engages a seat 8 in the lower end of hopper 5 for effectively closing said hopper. An arm 9 extends rearwardly from the rear hinged end of the door 6 from which arm depends a threaded rod 10 on which is slidably mounted an adjustable counter weight 11 for holding the door 6 closed when the car is running below a predetermined speed or standing still, said weight being adjusted and held on said rod by a nut 12 screwing on 60 said rod below the weight. An operating lever 13 is formed in two sections 14 and 15, pivoted together by a horizontal pivot as at 16, and is formed with forks 17 and 18 at its forward and rear ends respectively, 65 the fork 17 lying in a horizontal plane to straddle the hopper 5, and the ends of said fork being pivoted at 19 to opposite sides of said hopper with the lever 13 extending rearwardly from the hopper, thus fulcruming the forward end of the lever 13 to said 70 hopper. The door arm 9 and the section 14 of lever 13 are pivotally connected to the ends of a link 20 as at 21 and 22 respectively. A flat spring 23 is pivoted at its lower end 75 at 24 to the rear side of the hopper 5 and extends upwardly through the lever fork 17 and carries a set screw 25 at its upper end which engages the rear side of said 80 hopper for adjusting the tension of said 85 spring in the respective engagement of the sockets 26 and 27, formed therein, with a roller 28 journaled in the crotch of fork 17, for respectively locking the door 6 in 90 closed or open position. A pair of arms 29 and 30 extend vertically from the lower and upper edges respectively of the lever section 14, and a pair of arms 31 and 32 extend vertically from the lower and upper 95 edges respectively of the lever section 15. A coil spring 33 is connected at its ends to the arms 29 and 31 respectively and a coil 100 spring 34 is connected respectively at its ends to the arms 30 and 32. A fly ball governor 35, which is driven by 105 a bevel gear 36, is mounted on a hanger 37 suspended from the under side of the car floor 1. On the operating collar 38 of said

governor is a pin 39 which is engaged by the fork 18 of the lever 13. A short shaft 40 is journaled in the lower part of hanger 37 on one end of which shaft is a bevel gear 41 in mesh with the bevel gear 36. A telescopic shaft 42 is connected at one end by universal joint 43 to the shaft 40 and at its other end by a universal joint 44 to one end of a shaft 45 journaled in bearings 46 and 47 on the car truck 2. On the other end of the shaft 45 is secured a bevel pinion 49 in mesh with a split bevel gear 50 which is clamped to the car axle 51.

When the car is standing still or running below a predetermined rate of speed the weight 11 holds the door 6 of the hopper 5 closed. The governor 35 is driven by the car axle 51 through the medium of gear 50, pinion 49, shaft 45, universal joint 44, telescopic shaft 42, universal joint 43, shaft 40, and bevel gears 41 and 36. When the car speeds up the governor 35 swings the lever section 15 upwardly on its pivot 16, against the tension of lower spring 33. When the speed of the car rises to a predetermined degree the governor raises the lever section 15 to such point as to place the spring 33 under sufficient tension to swing lever section 14 upwardly and jump the roller 28 out of the socket 26 and into socket 27, so that the lever 13 straightening under the tension of said spring will through the link 20 quickly open the hopper door 6. When the speed of the car falls below said predetermined degree the governor will swing the lever section 15 downwardly against the tension of upper spring 34 until the tension of said spring is sufficient to swing the lever section 14 downwardly and jump the roller 28 out of the socket 27 into the socket 26 so that the lever 13 through link 20 will close the hopper door 6.

Having thus described my invention I claim:

1. A railway closet trap including a hopper adapted to receive the efflux from the closet, a door for said hopper, a lever, formed in two sections pivoted together, a spring extending across the pivot of said sections and connected at its ends respectively to said sections, a link connected to said door and to one of said sections, and means engaging the other section for swing-

ing said section against the tension of said spring so that said spring will swing the other section and open said door quickly when the speed of the car reaches a predetermined degree, and for swinging said lever to close said door when the speed of the car falls below said predetermined degree.

2. A railway closet trap including a hopper adapted to receive the efflux from the closet, a door for said hopper, a lever formed in two sections pivoted together, a pair of springs extending across the pivot of said sections and connected at their ends respectively to said sections, a link connected to said door and to one of said sections, and means engaging the other section for swinging said section against the tension of one of said springs, so that said spring will open said door quickly when the speed of the car reaches a predetermined degree, and for swinging said section against the tension of the other spring so that said spring will close said door quickly when the speed of the car falls below said predetermined degree.

3. A railway closet trap including a hopper adapted to receive the efflux of the closet, a door for said hopper, a lever formed in two sections pivoted together, a pair of springs extending across the pivot of said sections and connected at their ends respectively to said sections, a link connected to said door and to one of said sections, a roller on said section, a flat spring formed with two sockets for respectively engaging said roller, and means engaging the other section for swinging said section against the tension of one of said pair of springs, so that said spring will swing the first section to jump said roller out of one socket into the other socket and open said door quickly and lock said door open when the speed of the car reaches a predetermined degree, and for swinging said other section against the tension of the other of said pair of springs, so that said spring will swing the first section to jump said roller out of the latter socket back into the first socket and close said door quickly and lock said door closed when the speed of the car falls below said predetermined degree.

FORREST L. SCOTT.
